UNITED STATES PATENT OFFICE.

SIMON LEVIN, OF NEW YORK, N. Y.

DESIGN FOR A CIGAR.

SPECIFICATION forming part of Design No. 35,310, dated November 26, 1901.

Application filed June 22, 1901. Serial No. 65,699. Term of patent 14 years.

To all whom it may concern:

Be it known that I, SIMON LEVIN, a citizen of the United States, and a resident of the city of New York, borough of Manhattan, in the county and State of New York, have invented and produced a new and original Design for a Cigar, of which the following is a full, clear, and exact specification.

Reference is to be had to the accompanying drawing, forming a part of this specification, in which the figure is a perspective view of a cigar, showing my design.

My design for a cigar consists in the body portion 1, having between its ends a well-defined annular depression, which gradually diminishes in depth from its center outward in both directions, the portions of the cigar-

body outward of the depression being gradually reduced in diameter from their centers in both directions, one end of the complete cigar being blunt, while the other end is pointed.

Having thus described my invention, I claim as new and desire to secure by Letters Patent—

The design for a cigar as herein shown and described.

In testimony whereof I have signed my name to this specification in the presence of two subscribing witnesses.

SIMON LEVIN.
